US00D873358S

(12) **United States Design Patent** (10) **Patent No.:** **US D873,358 S**
(45) **Date of Patent:** **** Jan. 21, 2020**

(54) **GOLF CLUB HEAD**

(71) Applicant: **KARSTEN MANUFACTURING CORPORATION**, Phoenix, AZ (US)

(72) Inventors: **Daniel K. Lee**, Chandler, AZ (US);
Calvin S. Wang, Chandler, AZ (US);
Xiaojian Chen, Phoenix, AZ (US)

(73) Assignee: **Karsten Manufacturing Corporation**,
Phoenix, AZ (US)

(**) Term: **15 Years**

(21) Appl. No.: **29/666,053**

(22) Filed: **Oct. 9, 2018**

(51) LOC (12) Cl. **21-02**

(52) U.S. Cl.

USPC **D21/744**

Primary Examiner — Mitchell I. Siegel

(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1;
FIG. 8 is a toe side view of the golf club head of FIG. 1;
FIG. 9 is a top perspective of a second embodiment of the golf club head;
FIG. 10 is a bottom perspective view of the golf club head of FIG. 9;
FIG. 11 is a top view of the golf club head of FIG. 9;
FIG. 12 is a bottom view of the golf club head of FIG. 9;
FIG. 13 is a front view of the golf club head of FIG. 9;
FIG. 14 is a rear view of the golf club head of FIG. 9;
FIG. 15 is a heel side view of the golf club head of FIG. 9; and,
FIG. 16 is a toe side view of the golf club head of FIG. 9. The broken lines shown are included for the purpose of illustrating unclaimed subject matter and forms no part of the claimed design. A portion of the bottom surface disclosed on FIGS. 9-16 is stippled heavier and lighter to illustrate contrasting appearance.

1 Claim, 12 Drawing Sheets
